(57) **CLAIM**

The ornamental design for a tread portion of an automobile tire, as shown and described.

DESCRIPTION

FIG. 1 is a perspective view of the top, front and one side of a tread portion of an automobile tire showing my new design, it being understood that the tread pattern repeats itself uniformly throughout the circumference of the tire thereof;

FIG. 2 is a front elevational view thereof, the top and bottom plan views being identical thereto;

FIG. 3 is a rear elevational view thereof;

FIG. 4 is a right side elevational view thereof;

FIG. 5 is a left side elevational view thereof;

FIG. 6 is an enlarged fragmentary front elevational view thereof; and,

FIG. 7 is an enlarged cross-sectional view thereof taken along the line 7—7 as shown in FIG. 6.

The elements shown in broken lines are for illustrative purposes only and form no part of the claimed design.

The broken lines immediately adjacent the outer edge of the shoulder blocks form the peripheral boundary of the claimed design.
